UNITED STATES PATENT OFFICE.

CHARLES G. CUNNINGHAM, OF NEW YORK, N. Y.

CENTRIFUGALLY-OPERATED CONTACT DEVICE.

1,132,653.

Specification of Letters Patent. Patented Mar. 23, 1915.

Application filed September 9, 1913. Serial No. 788,794.

To all whom it may concern:

Be it known that I, CHARLES G. CUNNINGHAM, a citizen of the United States, residing in the city of New York, county of Bronx, State of New York, have made a certain new and useful Invention in Centrifugally-Operated Contact Devices, of which the following is a specification.

This invention relates to centrifugally operated contact devices for automatically opening and controlling electric circuits.

The object of the invention is to provide means which are simple and efficient for automatically maintaining an electric circuit open through centrifugal action and to close said circuit when the centrifugal action ceases.

Other objects of the invention will appear more fully hereinafter.

The invention consists substantially in the construction, combination, location and relative arrangement of parts, all as will be more fully hereinafter set forth, as shown in the accompanying drawing and finally

25 pointed out in the appended claims.

Referring to the accompanying drawing, Figure 1 is a view in central longitudinal section of a centrifugally operated contact controlling device embodying my invention, 30 a gearing for producing the centrifugal action being shown connected thereto, the centrifugally acting devices being arranged in an inclosing box, the top of which is shown open. Fig. 2 is a top plan view of the central longitudinal section of a centrifugally operated contact controlling mechanism, showing diagrammatically the application of the same in one form of use thereof. Fig. 3 is a view in transverse section on the line 3, 3, Fig. 2, looking in the direction of the arrows. Fig. 4 is a view partly in longitudinal central section and partly in side elevation of a contact controlling device embodying my invention showing a modified form thereof.

45 The same part is designated by the same reference numeral wherever it occurs throughout the several views.

In the drawing, reference numeral 5 designates a block or head which is designed to 50 be rotated at a speed sufficient to develop the required centrifugal action, and preferably made of insulating material. A fiber block 5 will answer the purpose. The head or block 5 is connected to a driving shaft 6 through 55 which rotary movement is imparted thereto. This shaft may be a motor shaft or it may

be geared to driving shaft, such, for instance, as indicated at 7 Fig. 1 through any suitable arrangement of gearing 8, 9 for imparting rotary motion to the head of sufficiently high speed. An opening is formed 60 from one side face of the block or head 5 part way through the longitudinal center of the block into which opening is inserted one end of a sleeve 10. This sleeve is preferably of conducting material, and upon or with which co-operates a collector brush 11, see Fig. 2. Extending longitudinally 65 through the sleeve 10 is a rod 12 but insulated from said sleeve by interposed bushings 13, 14 of insulating material. The outer end of the rod 12 extends beyond the outer edge of the sleeve 10 and carries a conductive disk or portion 15 upon or with which co-operates a current collector or contact brush 16, the insulating bushing 14 being interposed between the end of sleeve 10 and the portion 15. The inner end of the insulating bushing 13 extends somewhat beyond the inner end of sleeve 10 and serves to 70 maintain a head 17 formed at the inner end of rod 12, insulated from the inner end of sleeve 12.

Formed radially through the body of the head or block 5 are pockets or openings 18, 85 which extend into the central opening in said block or head which receives the head 17, insulating bushing 13 and conductive sleeve 10. Any desired number of passages 18 may be employed. Under ordinary circumstances and for practical purposes I have found that four of such pockets equally spaced apart peripherally well answers the purpose but my invention is not to be limited or restricted in this respect. The passages 18 may be closed at their outer ends 90 in any suitable or convenient manner. I have shown screw-plugs 19 for this purpose.

In accordance with my invention, I propose to place within each of the passages 18 100 a suitable electrically bridging element which may be of any suitable conducting material, such, for instance, as mercury, as indicated at 20, Figs. 1 and 3, or a metallic ball 21, as indicated in Fig. 4. It is obvious 105 that other substances or material may be employed and therefore the mercury and ball forms are mentioned as illustrative of suitable and convenient means for the purpose. The bridging material, when the head or block 5 is stationary, in the passage 110 or passages 18, which are above the horizon-

tal plane of the axis of rotation of the head or block will gravitate to the innermost end or ends of such passage or passages and when occupying this position, such bridging material will serve to bridge the space separating the proximate end of the conducting sleeve 10 and the adjacent surface of the head 17, thereby placing the conducting sleeve 10, which would otherwise be insulated therefrom into electrical connection with the head 17 and hence, through the rod 12, with the conducting portion 15, thereby bringing the brushes 11, 16 into electrical circuit connection with respect to each other. When, however, rotary movement is imparted to the head or block 5 at sufficient speed the bridging substance 20, or 21, through centrifugal action will travel radially or will be thrown out of bridging relation with respect to the sleeve 10 and head 17, thereby breaking the circuit between the brushes 11, 16.

A centrifugally operated contact controlling device having the construction above described is applicable for use in any situation and for any purpose where it may be desired to automatically control an electric circuit, the control being effected through centrifugal action of the device upon the circuit bridging substance or material employed. For instance, a device of the character described is suitable for closing the circuit of a magnetic or other electrically operated brake upon the arrest of a motor. Another application of such a device is for closing or opening a signal circuit for the purpose of showing when a motor, engine, or other apparatus stops or starts. Another practical application of the device is for the purpose of controlling signal systems employed in connection with the operation of elevators whereby when a push button is employed to operate a stop signal at any floor served by the elevator, it will not require a second operation of the push button where a car for any reason passes a floor without stopping there at any response to the signal, the signal continuing in operation until the next or some subsequent car stops at the required floor. Another use to which a device embodying my invention may be applied is to automatically open the circuit of the charging generator for a storage battery in order to prevent a discharge from the battery back through the generator in case the generator stops such an application of practical use of my invention is diagrammatically indicated in Fig. 2 wherein a storage battery indicated at 22 is shown arranged in the circuit of a charging generator 23, the charging circuit of which includes a switch device 24, controlled by a solenoid 25 in such relation that when the circuit of the solenoid is open the charging circuit of the generator to the

storage battery is closed and when the solenoid circuit is closed and the solenoid energized the charging circuit of the generator to the battery is opened. The circuit of the solenoid includes any suitable source of current such for instance as a battery 26, and also the brushes 11, 16. With this arrangement it will be obvious that with the head or block 5 under rotation at sufficiently high speed the circuit connection between the brushes 11, 16 will be broken, thereby breaking the circuit of solenoid 25 and permitting the charging circuit of generator 23 to the storage battery 22, to be closed. In this case, of course, the motor which drives the generator 23 may serve to rotate the block or head 5. Should the generator stop or its driving motor be arrested the circuit of the solenoid 25 is automatically closed, thereby opening the charging circuit of the storage battery and preventing the latter from discharging back through the generator.

In Fig. 1 I have shown the contact controlling apparatus placed within a box or casing 27, the door 28 of which is shown open.

Where I employ a more or less fluid bridging substance, such for instance, as mercury, I prefer to so mount the sleeve 10 and rod 12 in the block 5 as to be carried thereby and to rotate therewith, in which case the contact brushes or collectors 11 and 16 are employed. In this case only one line circuit is employed and as the apparatus is supported wholly independently of the frame of the machine in connection with which it is used, and is merely gear connected thereto, I avoid the danger of and the complication incident to grounding the circuit through the frame. In its broadest scope, however, as defined in the claims, my invention is not to be limited or restricted to this structure and arrangement.

Having now set forth the object and nature of my invention and constructions embodying the principles thereof, what I claim as new and useful and of my own invention and desire to secure by Letters Patent is:

1. A centrifugally operated contact controlling device including a block or member of insulating material having radial passages and an axial recess in one face thereof, a rotatable shaft on which said block or member is mounted to be rotated thereby, circuit terminals insulated from each other independent of said shaft and extending into said recess to a point opposite said passages, and bridging material carried in said passages and subject to the centrifugal action of said block or member for controlling the circuit bridging of the space between said terminals.

2. In a centrifugally operated contact controlling device, a head or block of insulat-

- ing material having an axial recess in one face thereof and radial passages communicating with said recess, circuit terminals insulated from each other and extending into 5 said axial recess to a point opposite said passages, and circuit bridging material contained loosely in said passages to bridge the space between said terminals when said head is at rest.
- 10 3. In a centrifugally operated contact controlling device, a rotatable head of insulating material having an axial recess in one face thereof and radial passages communicating with said recess, circuit terminals insulated from each other and extending into 15 said recess and centrifugally acting contact material carried in said radial passages to control the circuit connections between said terminals.
- 20 4. A centrifugally operated contact controlling device including a rotatable head of insulating material having an axial recess in one face thereof and radial passages communicating with said recess, contact terminals 25 extending into said recess to a point opposite said passages, said terminals being insulated from each other, and movable
- trifugal acting means loosely carried in said passages for controlling the circuit connection between said terminals. 30
5. In a centrifugally operated contact controlling device a rotatable head of insulating material having an axial recess and radial passages communicating with said recess, a contact sleeve extending into the axial recess 35 in said head, a contact rod extending through but insulated from said sleeve and having a head juxtaposed with reference to the inner end of said sleeve, the juxtaposed head and sleeve end extending into co-operative relation with respect to said radial passages and loosely mounted bridging means contained in said passages to control the circuit connection between said head and sleeve and contact brushes respectively co-operating 40 with said sleeve and head.
- In testimony whereof I have hereunto set my hand in the presence of the subscribing witnesses, on this 8th day of September A. D., 1913.
- CHARLES G. CUNNINGHAM.
